UNITED STATES PATENT OFFICE.

MAX VON RECKLINGHAUSEN, OF PARIS, FRANCE, ASSIGNOR, BY MESNE ASSIGNMENTS,
TO COOPER HEWITT ELECTRIC COMPANY, OF HOBOKEN, NEW JERSEY, A CORPORA-
TION OF NEW JERSEY.

ELECTRODE FOR GAS OR VAPOR ELECTRIC APPARATUS.

1,091,244.

Specification of Letters Patent. Patented Mar. 24, 1914.

Original application filed February 14, 1903, Serial No. 143,317. Divided and this application filed February 5, 1907. Serial No. 355,845.

To all whom it may concern:

Be it known that I, MAX VON RECKLINGHAUSEN, a subject of the Emperor of Germany, and resident of Paris, France, have 5 invented certain new and useful Improvements in Electrodes for Gas or Vapor Electric Apparatus, of which the following is a specification.

The present invention is applicable to the 10 general class of gas or vapor electric apparatus invented by Peter Cooper Hewitt and described and shown in certain patents issued to him on the 17th day of September, 1901. In apparatus of this class whether 15 used for the purpose of giving light or for any other purpose, it has been customary, when found convenient, to use as the material for one or more of the electrodes a conducting fluid such as mercury. During the 20 operation of the apparatus some of this mercury is vaporized and afterward cooled, usually in a special cooling chamber. Hitherto no special means have been devised for securing an accurate re-distribution of the 25 mercury after the condensation due to cooling, although devices have been suggested for carrying some of the mercury which is carried away from the negative electrode back to the said electrode after condensation, 30 say, through a special tube provided for the purpose.

The present invention aims at providing a more accurately gaged re-distribution of the mercury, as will fully appear hereinafter. 35 For example, I may provide suitable pockets for containing the several electrodes of mercury or other conducting fluid, such pockets being devised so as to contain the proper amount of fluid to serve as an electrode and 40 to present within the chamber of the apparatus a suitable amount of surface for the purpose for which the apparatus is designed. I may then so dispose the cooling chamber in which the greater part of the 45 condensation takes place with relation to the several pockets as to provide for a return of the mercury which may have been withdrawn from the said pockets during the operation of the lamp, or by any means what- 50 soever to the said pockets in succession, so that any pocket which shall have received its proper amount of mercury, or other conducting fluid will, on the entrance of any

more fluid, of condensation overflow and transfer the overflow to the next pocket and 55 so on until all the pockets in the series are suitably filled. I may accomplish this by giving to the apparatus a suitable slope running from the cooling or condensing chamber downward whereby the force of gravity 60 will carry the condensed vapors from pocket to pocket as described. Should it be desired to utilize a non-fluid or solid substance as one of the electrodes, or a fluid of another character, or should it for any reason be 65 undesirable to deliver the condensed vapor to one of the electrodes, the tube may be turned away from the general downward slope and may thus be removed from the path of flow. It is now known that apparatus of this class is often provided with a considerable number of electrodes. For example, a well-known form of apparatus contains a single negative electrode and a plurality of positive electrodes, while a supplemental electrode is often employed as one terminal of a direct current circuit adapted to maintain the passage of current of one direction through the apparatus. 70

I have illustrated my invention in the accompanying drawings, in which—

Figure 1 is a section of a gas or vapor electric apparatus embodying my invention; Figs. 2, 3 and 4 are similar views of modifications.

Referring to the drawings, 1 is a container 85 adapted to inclose a conducting gas or vapor and being provided with pockets 2, 3, 4, 5 and 6, as shown. These pockets are adapted to contain a conducting fluid which in 90 this instance is represented as mercury, and the pockets 2, 3 and 5, may be assumed to contain the mercury constituting positive electrodes, while the pocket 4, may contain the mercury constituting the negative electrode. 95 Suitable lead wires are connected through the walls of the pockets with the electrodes contained therein. It is unnecessary to give 100 in detail the operation of an apparatus of this sort further than to say that such operation has for one of its effects the vaporization of a portion of the conducting fluid and the circulation of the vapor through the ap- 105 paratus.

As a feature of the apparatus, a cooling chamber, as 7, is generally provided, and in this instance I locate such chamber at the summit of the apparatus, and incline the 5 tubular portion 1 with respect to the said cooling chamber so as to give to the mercury which is condensed therein a tendency to descend along the tube by the action of gravity. In its descent the condensed vapor will first 10 enter the pocket 2, and in case that pocket has been depleted of a portion of its mercury, the descending mercury will now refill it, and when such refilling has taken place, the pocket will overflow and the mercury 15 will pass into the next pocket in the series and so on. In this way the several pockets are maintained full, or nearly so, at all times, and the mercury which is withdrawn by the operation of the apparatus is re-dis- 20 tributed in such a way as to restore normal conditions.

In Fig. 2 the same principle is illustrated, the pockets in this instance being two in number, one of them, as 8, containing the 25 positive electrode, and the other, as 9, the negative electrode. In both instances, suitable lead-wires are connected through the walls of the pocket with the electrodes contained therein.

Fig. 3 illustrates a construction in which 30 one of the electrodes, say the supplemental electrode, appearing at 10, is of some solid substance such as iron. The electrode 10 is arranged in a raised portion of the tube 35 and is not subject to being fed by the downward flow of the conducting fluid, as is the case with the other electrodes.

Short circuits between the electrodes during the transfer of fluid from one pocket to 40 another may be prevented by introducing obstructions just in advance of each pocket, as illustrated at 11, 11. The fluid on striking these obstructions will be momentarily checked and on leaving them will be accelerated so that there is not likely to be a 45 continuous stream of mercury between two successive pockets.

The means already described are merely 50 illustrative of typical forms of devices whereby the present invention may be carried out. Many other embodiments of the invention might be made without substantial departure from the principle of this invention. One such example is illustrated in 55 Fig. 4, wherein the negative electrode is represented as a puddle of mercury, 12, connected to a suitable lead-wire, and the positive electrode is shown as a column, 13, of mercury inclosed within an open-mouthed tubular extension, 14, of the container 1. The open end of the tube 14 terminates inside a vessel, 15, containing mercury, and the positive lead-wire is connected with this vessel or 60 with the mercury therein in any suitable manner. The column of mercury 13 is main-

tained at its proper height by atmospheric pressure so as to present a suitable amount of electrode surface within the chamber of the container 1. Another tubular extension, 16, of the container 1 is adapted to receive the mercury which is condensed in the cooling end 7 of the container. Here gravity carries down the condensed vapor through the tube 16, the arrangement being such that the mercury near the top of the tube passes 70 down in the form of drops until it meets the solid column of mercury which is maintained by atmospheric pressure at a certain height, inasmuch as the tube 16 dips into a vessel 17 containing mercury. I lead from the vessel 17 a pipe 18 connected with a suitable pump, 19, beyond which a pipe, 20, containing a stop cock, 21, terminates above the vessel 15. When the level of the mercury in the column 13 becomes too low, the pump 19 is put in operation, the stop-cock 21 is 75 opened, and the level is raised by adding to the height of the mercury in the vessel 15. Any excessive depletion of the mercury constituting the electrode 12 may be compensated for by carrying on the pumping process until some of the mercury from the top of the column 13 overflows in the direction 80 of the electrode 12.

The circulation of the mercury and the consequent reconstruction of the electrodes in the apparatus illustrated in Fig. 4, is manifestly not dependent upon the condensation of mercury, as the pump 19 may be operated to cause a circulation of the 90 mercury often enough to keep the electrodes in their normal condition quite independently of the condensation in the cooling chamber 7. Whatever excess of mercury may thus be introduced into the container 95 will pass beyond the electrode 12, over into the top of the tube 16.

This application is a division of my application Serial Number 143,317, filed February 14, 1903.

I claim as my invention:

1. In a vapor electric device, the combination of a container, multiple positive electrodes of mercury, an intermediate mercury negative electrode, and means whereby fluid transferred from one to another of said electrodes passes in separate and disconnected portions.

2. In a vapor electric device, a container, a plurality of main positive electrodes located therein in a continuous series, and a negative electrode interposed between at least two of said positive electrodes.

3. In a vapor electric device, a container, a plurality of main positive electrodes there- 120 in and a negative electrode interposed between at least two of said positive electrodes.

4. A vapor rectifier comprising an exhausted container and a plurality of positive electrodes located in a continuous series, 125

and a negative electrode interposed between at least two of said positive electrodes.

5. A vapor rectifier comprising an exhausted container, a plurality of positive electrodes and a main negative electrode interposed between at least two of said positive electrodes.

6. A vapor rectifier comprising an inclined exhausted container and a plurality of positive electrodes located in a continu-

ous series at the bottom of the incline and a negative electrode interposed between at least two of said positive electrodes.

Signed at Paris, France, this 22d day of January, A. D. 1907.

MAX VON RECKLINGHAUSEN.
